[57] CLAIM

The ornamental design for an ice dispenser, as shown and described.

DESCRIPTION

FIG. 1 is a right, front perspective view of an ice dispenser showing the new design (the dashed lines showing of the internal mechanism in this and the following figures are for illustrative purposes only and form no part of the claimed design);

FIG. 2 is a front elevational view thereof;

FIG. 3 is a right side elevational view thereof, the left side elevational view being a mirror image thereof;

FIG. 4 is a rear elevational view thereof;

FIG. 5 is a top plan view thereof; and,

FIG. 6 is a bottom plan view thereof.
